(No Model.)

G. H. PERKINS.
Nailing Machine.

No. 240,332.

Patented April 19, 1881.

UNITED STATES PATENT OFFICE

GEORGE H. PERKINS, OF PHILADELPHIA, PENNSYLVANIA.

NAILING-MACHINE.

SPECIFICATION forming part of Letters Patent No. 240,332, dated April 19, 1881.

Application filed June 21, 1880. (No model.)

To all whom it may concern:

Be it known that I, GEORGE H. PERKINS, of Philadelphia, Pennsylvania, have invented an Improved Machine for Nailing Boxes, of 5 which the following is a specification.

My invention relates in general to the class of mechanisms which are employed to automatically and continuously drive nails into material to be united; but it relates more specifically to the class of mechanisms employed to nail together wooden boxes, such as are employed in the incasing of petroleum-cans and the like. It is adapted, however, to the nailing together of various kinds of material.

15 Of the drawings, Figure 1 is a central sectional side elevation of a machine embodying my invention; Fig. 2, a front elevation of the same; Fig. 3, a top-plan sectional view of the same, on the line a' a' of Fig. 1; Fig. 4, a sectional side elevation of a nail-holder and nail-driver invented by me and forming the subject-matter of an application for patent, signed upon the same day and filed contemporaneously with this application, and denominated by me 20 Case A; Fig. 5, a front elevation of the same; Fig. 6, a top section on the line b' b' of Fig. 4.

In my present apparatus a reciprocating cross-head operated from a driving crank-shaft has connected with it a series of connecting-rods, which are each secured to a wrist-pin connected with a separate plunger-carrier, each connecting-rod being separate from every other, and being adapted to operate its individual plunger-carrier in whatever position or 35 inclination the latter may have been placed.

In the above construction my present apparatus differs broadly from any previous box-nailing machine in that said construction enables the driving of nails at angles either opposite, varying, or coincident.

In the drawings, A A are vertical standards, constituting the sides of the frame-work of the machine, and united together above in a transverse head-bar, B. Below they spread 45 out to form a base, C, of suitable configuration to support in bearings D a driving-axle, E, operated by a driving-pulley, F, and provided with a crank, G, to the wrist-pin of which is secured a pitman, H, passing vertically upward to a cross-head, I, to which it is secured by a pivot-pin, J. It is obvious that the revo-

lution of the axle will cause the reciprocation of the cross-head.

K is a treadle in the base of the frame-work, connected with a clutch device, L, known as 55 the "Bliss clutch," of such familiar construction to all mechanics as not to require explanation here. The operation of the clutch is to throw the driving-pulley into and out of gear alternately at the beginning and end of 60 each reciprocation of the plunger, its action being regulated by the treadle.

M are ways secured to the face-plate N of the machine, in which the cross-head plays.

In front of the face-plate is the table O, upon 65 which the box to be nailed is supported, adapted to be raised or lowered to the proper adjustment by means of screw-shafts P, to which it is threaded and by which it is supported, said shafts being operated by a bevel-gear, Q, in 70 the base of the frame-work.

R are connecting-rods, a series of which, corresponding in number to the number of nail-holders, is employed. They are each separately pivoted to the cross-head. These connecting-rods extend upward and attach to wrist-pins projecting from the plunger-carrier of each nail-holder, and are adapted to be adjusted with any lateral adjustment of the nail-holders, or with any inclination of the same, 75 so that they act invariably, upon the reciprocation of the cross-head, to operate the plungers, in whatever position the latter may have been placed.

The nail-holders represented in fourth, fifth, 80 and sixth views of the drawings constitute the subject-matter of an application filed by me (as Case A) contemporaneously with this, as hereinbefore referred to.

The separate connecting-rods R of my machine are each attached to a separate wrist-pin, f, connected with the plunger-carriers of said nail-holders. These nail-holders consist, essentially, of a carrier-guide, within which a plunger-carrier, e, travels. The carrier-guide is 90 adapted, by means of a clamp-plate, c, or similar device, to be set at varying lateral angles upon the frame-work. Depending from the carrier-guide is the nail-holder proper, m, a tubular receptacle incasing a pressure-spring, 100 p, and adapted to lift upwardly and backwardly as the plunger forces the nail from it.

The nail-holder is secured to the plunger-guide in the direct line of the stroke of the plunger and assumes the same angle with the carrier-guide.

5 Such being the construction of my invention, it is obvious that when the box is placed upon the table or bed, the machine thrown into action, and each of the plungers thereby caused to advance, the nails, one of which has 10 been fed into each nail-holder, will be driven into the material to be united, at whatever inclination the nail-holders may have been previously set, and as the machine is capable of adjustment with respect to its nail-holders, 15 each independently of the other, it is obvious that the fastening of the box by varied inclination of the nails may be made extremely secure.

Any number of nail-holders may, of course, be applied, their application to the cross-bars 20 of the machine being extremely simple, and the reciprocating cross-head being best constructed with a large number of pivots, so as to adapt it to receive a large number of connecting-rods.

25 The advantages incident to my machine are, that it enables the employment of the Bliss clutch, thus dispensing with the use of other elaborate clutches, or clutches which may be uncertain in their operation; that it enables 30 the omission of sectors and other kindred devices to drive the plungers, and enables the employment of a pulling mechanism which acts direct upon the plunger-carriers from the cross-bar without any intermediate mechanisms other than connecting-rods; that the 35 action of the crank and pitman in the operation of pulling down the cross-head and its series of connecting-rods attached to the nail-plun-

gers is both simple and certain; and that the employment of the nail-holders enables, as 40 heretofore stated, the angular driving of the nails, and imparts to the machine all the advantages which are incident to the nail-holder, as described in the application for patent, which I have made for the same.

45 Having thus described my invention, I claim and desire to secure by Letters Patent of the United States—

1. In a machine for nailing boxes, the combination of a reciprocating cross-head, a series of independent plungers, and a series of independent connecting-rods, one end of each of which is connected with the cross-head, and the other end of each of which is connected with a separate plunger, substantially in the 50 manner described, so that the downward pull of the cross-head, acting through the separate connecting-rods, operates the plungers, substantially as described.

55 2. In a machine for nailing boxes, the combination of a reciprocating cross-head, operated as described, with a series of angularly and separately adjustable plungers, by means of a series of separate connecting-rods, whereby the downward pull of the cross-head, acting through the separate connecting-rods upon the separately-adjusted plungers, causes the driving of the nails at angles corresponding to those at which the plungers have been disposed, substantially as shown and described.

60 In testimony whereof I have hereunto signed my name this 1st day of May, A. D. 1880.

GEORGE H. PERKINS.

In presence of—

C. B. TAYLOR,
J. BONSALL TAYLOR.
